UNITED STATES PATENT OFFICE.

FRANK MCINTYRE, OF NEW YORK, N. Y., ASSIGNOR TO THE EAGLE PENCIL COMPANY, OF SAME PLACE.

DESIGN FOR A PENHOLDER.

SPECIFICATION forming part of Design No. 23,501, dated July 24, 1894.

Application filed June 18, 1894. Serial No. 514,989. Term of patent 14 years.

To all whom it may concern:

Be it known that I, FRANK MCINTYRE, of the city, county, and State of New York, have invented a new and original Design for Penholders, of which the following is a specification, reference being made to the accompanying drawings, in which—

Figure 1 is a view of a penholder embodying the design. Fig. 2 is a cross section enlarged through the lower or grip portion of the handle.

Under my invention the tapering upper portion of the handle has a smooth exterior and the exterior surface of the grip or lower portion of the handle is subdivided into figures A, of parallelogram shape, between which

intervene section lines B extending spirally around the sheath and intersecting sunken straight lines C extending lengthwise of the sheath.

What I claim, and desire to secure by Letters Patent, is—

The design for a penholder as herein illustrated.

In testimony whereof I have hereunto set my hand, before two subscribing witnesses, this 8th day of June, 1894.

FRANK MCINTYRE.
